UNITED STATES PATENT OFFICE.

ALBERT BABENDREER, OF OCEAN SPRINGS, MISSISSIPPI.

PROCESS AND APPARATUS FOR THE CIRCULATION OF FLUIDS WITHIN CARRIERS.

1,325,773.

Specification of Letters Patent.

Patented Dec. 23, 1919.

Application filed January 31, 1918. Serial No. 214,756.

To all whom it may concern:

Be it known that I, ALBERT BABENDREER, a citizen of the United States of America, residing at Ocean Springs, in the county of

5 Jackson and State of Mississippi, have invented certain new and useful Improvements in Processes and Apparatus for the Circulation of Fluids Within Carriers, of which the following is a specification.

10 My invention relates to a process and apparatus for the circulation of fluids either gaseous or liquid within ships, railway cars or like carriers, which in motion are subjected to irregular or abnormal movements.

15 The object of my invention is to utilize to the fullest possible extent the irregular movements of the ship or car while in travel as a power means for effecting the circulation of air, gas, or liquids as may be desired, and my invention is more particularly adapted for use with carriers of perishables wherein the circulation of the air, brine, or any refrigerating or drying medium will be conducive to the preservation of the perishables or the maintenance of the desired 25 temperature conditions.

I have conceived that employment may be made of the potential energy derivable by means of a weight so mounted as to move responsive to the abnormal movements of the carrier both vertically and laterally, such energy being imparted by any suitable mechanical transmission means to any suitable agency for effecting a forced movement of 35 the fluid to be circulated, such as a pump, blower, or equivalent device.

The preferred embodiment of my invention contemplates the use of a pendulum motor which derives its power from the vertical 40 jolting as well as the lateral swaying movements of the carrier and acts to operate a pump, preferably a diaphragm pump which acts in conjunction with any ordinary arrangement of intake and outlet valves to 45 force the desired circulation of the fluid. It is also contemplated by my invention that the pump may be connected at its intake and outlet so as to transfer the fluid between any desired points in the carrier.

50 The broad principles underlying my invention are susceptible of a wide variety of

mechanical applications and will be best understood by reference to the accompanying drawings which form a part of this specification and in which several of what I regard as the preferred embodiments of my invention 55 are illustrated.

According to the drawings:—

Figure 1 is a plan view of the diaphragm pump with a pendulum actuated lever for 60 operating it.

Fig. 2 is a side elevation of Fig. 1.

Fig. 3 shows a perspective view of a refrigerator car equipped with my invention and adapted for the circulation of brine. 65

Similar reference numerals refer to similar parts throughout the drawings.

Referring to the preferred embodiment of my invention illustrated in Figs. 1 and 2, I there show a pumping element as formed 70 by a circular dished plate 1 having a flat marginal flange 2 to which a rubber or any suitable elastic diaphragm 3 is marginally secured by means of a ring 4 which is riveted or bolted to the flange 2. The diaphragm 75 at its center is received between and stiffened by a pair of circular plates 5, 5, one lying above and the other below the diaphragm and being riveted therethrough by rivets 6 which are so packed as to be fluid 80 tight. To the lower plate 5 is made fast a hanger bracket 7 in which I pivot by means of a pin 8 one end of a lever 9 which is fulcrumed by a pivot pin 10 to a supporting U-shaped bracket 11, the ends of which are 85 out-turned and bolted to any suitable overhead support. On the end of the lever beyond its fulcrum I mount a pendulum 14 carrying a weight 15 on its lower end. The lever 9 is round so that the pendulum is free 90 to swing thereabout between collars 12 held fast by set screws 13, and the lever and pendulum tend to swing about the fulcrum point 10 when the pendulum responds to lateral movements or vertical jolts of the car 95 and they thus impart a reciprocation to the diaphragm 3. The chamber 16 in the diaphragm pump is connected by means of a pipe or conduit 17 to a valve casing 18 containing any suitable type of inlet check valve 100 19, beyond which the pipe 17 is continued to the desired point from which the air or fluid

is to be moved. The chamber 16 is connected by means of a pipe or conduit 20 with a valve casing 21 in which any suitable form of outlet check valve 22 works, the pipe 20 being extended beyond the valve casing to reach the point to which it is desired to deliver the air or fluid.

It being understood that the fulcrum pin 10 lies parallel with the long axis of the car, 10 as the carrier oscillates, sways from side to side or moves abnormally while traveling this motion is transmitted to the pendulum 14 which in turn transmits the motion through the lever 9 to the diaphragm 3, 15 causing the latter to rise and fall and in doing so to function in the manner well understood to suck in the fluid past the valve 19 and discharge it past valve 22, thus serving to transfer or propel the fluid acted 20 upon from any particular area within the carrier to any other area, the piping 17 and 20 being extended to the desired areas in any practicable manner. Obviously the 25 length of the pendulum, the dead weight of 15, and the distance between the fulcrum point 10 and the diaphragm pump are all variables which can be empirically fixed for the duty required of each particular apparatus. Referring to Fig. 3, it will be ob- 30 served that the weight 15 hangs near the bottom of the car while the lever 9 is ful- crumed near the top of the car, which serves as an illustration of any suitable carrier which is subject to abnormal movements in 35 travel. In such case, bearing in mind that the rocking or swaying movements of the car increase toward its top, the weight 15 acts on the pendulum in the first instance through its inertia to resist a movement of 40 the diaphragm responsive to the movement of its casing, and thus the initial movement to the diaphragm is imparted by the joint action of the sidewise motion of the car and the inertia of the weight. When the 45 pendulum follows the motion of the car, the return of the car to normal position or its sway over to the other side will act through the lever to reverse the movement of the diaphragm.

50 It will also be observed that the weight being suspended from the lever at a point substantially spaced from its fulcrum 10 will respond to the vertical or jolting movements of the carrier and will convert these 55 abnormal movements into a means for oscillating the diaphragm and operating the pump.

Referring to Fig. 3, a brine tank 60 at the end of the car is supplied with brine or like 60 refrigerating fluid in any manner as customarily practised. I have shown a refrigerating coil 61 disposed at the side of the car, it being understood that these coils may be of any suitable construction and 65 arrangement. The lower end of the coil is

connected to the discharge pipe 20 while the intake pipe 17 is connected to the lower portion of the tank. The upper end of the coil discharges into the top of the tank. As the diaphragm pump is operated the brine 70 is drawn from the tank and forced upwardly through the coil 61 and returned to the tank. Where it is desired to effect at the same time a change of air, any one of the means shown for operating the dia- 75 phragm pump may be employed with its pipe 17 extending to the bottom of the car and its pipe 20 to the top of the car if it be desired to draw air from the bottom and discharge it at the top of the car, but if the desire is to draw air from the top and carry it to the bottom, the arrangement of the pipes is reversed. The flange 2 of the pump carries lugs 62 perforated for the 80 reception of bolts or any suitable fastenings 85 by means of which it can be attached to the car at the desired point.

This invention is obviously especially adapted to the circulation of air in the holds of vessels and to force any refrigerating or 90 cooling medium to travel so as to best preserve perishable freight.

As the energy of my motor is derived by 95 its weight's inertia to abnormal carrier movements, its power is not obtained at the expense of the power required to propel the carrier but rather by the motor's opposition to such abnormal movements. The motor's power therefore is strictly a by-product derived advantageously to travel of the car- 100 rier.

This invention is not intended to be re- 105 stricted in scope to the specific embodiment shown, but contemplates such modifications as come within the spirit and scope of the claims.

Having thus described my invention, what I claim as new and desire to secure by Letters Patent, is:—

1. In an apparatus for the circulation of 110 fluids in a movable carrier, the combination of a fluid propelling means, a lever for transmitting motion to said fluid propelling means, a fulcrum for the lever, and a pendulum weight mounted on the lever in position 115 to oscillate the latter responsive to vertical and lateral movements imparted to the weight by the movement of the carrier.

2. In an apparatus for the circulation of 120 fluids in a carrier, the combination of a fluid propelling means, a vertically movable lever for imparting motion to said propelling means, a fulcrum for the lever, and a pendent weight connected to the lever at a point spaced from the fulcrum and disposed 125 to respond to vertical and lateral movements of the carrier.

3. In an apparatus for circulating fluids in a carrier, the combination of a fluid propelling means disposed in the upper portion 130

of the carrier, a substantially horizontally disposed lever having an intermediate fulcrum, the lever having an operating connection at one end with the fluid propelling means and having a pendulum weight pivotally mounted on its other end beyond the fulcrum, said weight having an elongated

hub forming its pivotal connection to the lever with the long axis of the hub bore disposed transversely of the carrier.

10

In testimony whereof I affix my signature.

ALBERT BABENDREER.
